CLAIM

The ornamental design for an ice pad for shoulder, as shown and described.

DESCRIPTION

FIG. 1 is a perspective view of an ice pad for shoulder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the ice pad for shoulder where the ice pad for shoulder is in a configuration of use; FIG. 10 is an enlarged view of portion 10 shown in FIG. 1; and,

FIG. 11 is an enlarged view of portion 11 shown in FIG. 7. The broken lines in the drawings depict environment of the ice pad for shoulder that form no part of the claimed design. The dash-dot lines represent the bounds of the detail view and form no part of the claimed design.
